a corporation of New York

Application August 8, 1946, Serial No. 132,365

Term of patent 14 years

(Cl. D33—7)

To all whom it may concern:

Be it known that I, Edwin Westlake, a citizen of the United States, residing at New York, in the county of New York and State of New York, have invented a new, original, and ornamental Design for a Table, Desk, or Similar Article, of which the following is a specification, reference being had to the accompanying drawing, forming part thereof.

In the drawing, Fig. 1 is a perspective view of my design, wherein the table, desk, or similar article, including the top and one leg and the cabinet which forms another leg, are shown in full lines, while the skirt or drape is shown in dotted lines for illustrative purposes only. The table or desk appears in Fig. 1 with its cabinet door open, while Fig. 2 is a front perspective view of the table or desk with the door of its angularly disposed cabinet closed.

I claim:

The ornamental design for a table, desk, or similar article, substantially as shown and described.

EDWIN WESTLAKE.
